UNITED STATES PATENT OFFICE.

ARTHUR LEWIS COCHRANE, OF TORONTO, ONTARIO, CANADA.

CLAMP.

1,398,126.

Specification of Letters Patent.

Patented Nov. 22, 1921.

Application filed August 22, 1921. Serial No. 494,248.

To all whom it may concern:

Be it known that I, ARTHUR LEWIS COCHRANE, of the city of Toronto, in the county of York, Province of Ontario, Canada, a subject of the King of Great Britain, have invented certain new and useful Improvements in Clamps, of which the following is a specification.

This invention relates to devices for fastening ropes, ties, laces and the like, and my object is to devise a clamp particularly adapted for use with straps and webbing which is simple, neat, easily constructed and assembled, and easily and quickly engaged or released.

I attain my object by means of the constructions hereinafter described and illustrated in the accompanying drawings in which—

20 Figure 1 is a plan view of my improved clamp;

Fig. 2 a longitudinal section of the same;

Fig. 3 a plan view of a slight modification;

25 Fig. 4 a side elevation of the same; and

Fig. 5 a longitudinal section showing the body member and clamping member in open position.

30 In the drawings like numerals of reference indicate corresponding parts in the different figures.

For the sake of clearness the device is shown in the drawings on an enlarged scale.

1 is a body member preferably formed of 35 sheet metal stamped to shape and having a forwardly extending tongue 2, and, intermediate its ends, a rearwardly facing shoulder 3 forming a bearing. 4 is a clamping member formed as an open quadrangular frame. While usually all four sides would be present in this frame, if it is desired one side may be omitted, as shown in Fig. 3, to facilitate the introduction between the body member and the clamping member of the

40 strap or webbing 5 which is to be gripped. The outer end of the body member is shaped and adapted to coöperate with the outer end of the tongue and clamp the strap or webbing, as will be understood on reference to

45 Fig. 2. The rear member 6 of the clamping member forms a journal against which bearing the shoulder 3 lies. The rear end of the body member is provided with a slot 7, which provides means for the permanent engagement of one end of the strap or strip 55 of webbing. The body member is held in

engagement with the journal 6 by means of a spring tongue 8, preferably formed integral with the body member and overlying at its free end the journal 6. With this arrangement the body member and clamp member are readily assembled entirely without the use of tools. It is preferable that the spring shall be utilized to tend to hold the body member and the clamping member 65 in clamping position. This is most readily effected by forming the flat 9 on the under side of the journal engaging the underlying part of the body member. It is evident that the body member cannot be rocked on the 70 journal without springing the tongue 8. The desired result is thus attained. A second flat 10 is also formed on the journal at its forward side, which lies flat against the underlying part of the body member when 75 the latter is swung up in the position, shown in Fig. 5. The body member cannot then be swung down without springing the tongue. The body member and clamping member may thus be held in an open position to facilitate the introduction of the end 80 of the strap or piece of webbing therebetween. The body member may then be swung down and will be resiliently held in the clamping position thereafter. It will be 85 evident that other deformations of the journal or the contacting parts might be employed to serve the purpose of the flats 9 and 10, and which would fall within the scope of my invention. It is preferable to employ 90 a loop to hold down the free end of the strap or webbing in which the device may be employed. I therefore prefer to form a loop 11 integral with the clamping member 4. A separate loop member 12 may, however, be 95 employed, as shown in Fig. 4, held in place in a loop formed by doubling the end of the strap 13.

It will be noted in the form shown in Fig. 4 integral lugs 14 are formed at the rear end 100 of the body member which are bent over to clamp the doubled end of the strap against the underlying part of the body member. Rivets or staples 15 will be employed to secure the parts together.

105 It will be seen from the construction described that the device is exceedingly simple, in one form comprising only two parts, which parts are easily assembled without the use of tools. The device is also very effective as a clamp, and is very easily operated.

110 It will be understood, of course, by simple

modification of the design it may be adapted for use for a great variety of forms of ties other than the flat strap shown.

What I claim as my invention is:—

- 5 1. A clamp comprising a body member formed with a forwardly extending tongue and a rearwardly facing shoulder intermediate its ends forming a bearing; a clamp member formed as an open quadrangular frame, the rear part of the body member 10 overlying the rear transverse member of the frame and forming a journal against which the bearing shoulder lies and having its outer end adapted to coöperate with the outer end of the tongue to form clamping means; a spring plate on the body member 15 engaging over the journal, the latter being shaped to engage one of the contacting parts to tend to hold the clamp member in clamping 20 position.
2. A clamp comprising a body member formed with a forwardly extending tongue and a rearwardly facing shoulder intermediate its ends forming a bearing; a clamp 25 member formed as an open quadrangular frame, the rear part of the body member overlying the rear transverse member of the frame and forming a journal against which the bearing shoulder lies and having its 30 outer end adapted to coöperate with the outer end of the tongue to form clamping means; a spring plate integral with the body member and engaging over the journal, the latter having a flat thereon engage- 35 able by the spring, whereby the spring tends to hold the clamp member in clamping position.
3. A clamp comprising a body member 40 formed with a forwardly extending tongue and a rearwardly facing shoulder intermediate its ends forming a bearing; a clamp member formed as an open quadrangular frame, the rear part of the body member 45 overlying the rear transverse member of the frame and forming a journal against which the bearing shoulder lies and having its outer end adapted to coöperate with the outer end of the tongue to form clamping means; a spring plate on the body member 50 engaging over the journal, the latter being shaped to engage one of the contacting parts to tend to hold the clamp member in either

of two positions, the clamping position or an open position.

4. A clamp comprising a body member 55 formed with a forwardly extending tongue and a rearwardly facing shoulder intermediate its ends forming a bearing; a clamp member formed as an open quadrangular frame, the rear part of the body member 60 overlying the rear transverse member of the frame and forming a journal against which the bearing shoulder lies and having its outer end adapted to coöperate with the outer end of the tongue to form clamping 65 means; and means on the body member overlying the journal and serving to hold the said member in position relative to the journal.

5. A clamp comprising a body member 70 formed with a forwardly extending tongue and a rearwardly facing shoulder intermediate its ends forming a bearing; a clamp member formed as an open quadrangular frame, the rear part of the body member 75 overlying the rear transverse member of the frame and forming a journal against which the bearing shoulder lies and having its outer end adapted to coöperate with the outer end of the tongue to form clamping 80 means; and spring means integral with the body member overlying the journal and serving to hold the said member in position relative to the journal.

6. A clamp comprising a body member 85 formed with a forwardly extending tongue and a rearwardly facing shoulder intermediate its ends forming a bearing; a clamp member formed as an open quadrangular frame, the rear part of the body member 90 overlying the rear transverse member of the frame and forming a journal against which the bearing shoulder lies and having its outer end adapted to coöperate with the outer end of the tongue to form clamping 95 means; means on the body member overlying the journal and serving to hold the said member in position relative to the journal; and a loop integral with the rear part of the frame through which a strap may be drawn. 100

Signed at Timagami this 20th day of July, 1921.

ARTHUR LEWIS COCHRANE.
